CHARCOAL GRILL

Myron M. Levin, Lincolnwood, Ill.
(4315 N. Lincoln Ave., Chicago, Ill. 60618)

Filed Feb. 28, 1967, Ser. No. 5,986

Term of patent 14 years

(Cl. D81—10)

FIGURE 1 is a top view of a charcoal grill showing my design, with the grid broken away for convenience of illustration only.

FIGURE 2 is a side view thereof.

FIGURE 3 is an end view thereof, and

FIGURE 4 is a sectional view taken on line 4-4 of FIGURE 1.

I claim:

The ornamental design for a charcoal grill, as shown and described.
